UNITED STATES PATENT OFFICE

2,579,594

PIPE WRENCH OF THE TYPE THAT EM-
BODIES OPPOSED JAW-EQUIPPED ARMS
WITH AN ADJUSTING SCREW THERE-
BETWEEN

Benjamin L. Lurie, Chicago, Ill.

Application April 20, 1949, Serial No. 88,581

5 Claims. (Cl. 81—91)

1

The present invention relates generally to wrenches. More particularly the invention relates to that type of wrench which is designed primarily for use in turning a pipe or like article and as its principal components or parts comprises: (1) an elongated housing-like body; (2) a handle which projects inwards from the inner end of the body; (3) a first arm which is connected fixedly to, and projects outwards from, the outer end of the body and is provided at its outer end with a laterally extending, pivotally mounted, pipe-engaging jaw; (4) a second arm which is disposed in opposed relation with the first arm and embodies at its outer end a laterally extending, pivotally mounted, pipe-engaging jaw; (5) an adjusting screw which is adapted to move the second arm to and from the first arm for the purpose of adjusting the wrench to grip pipes of different diameters or sizes and has its ends pivotally connected by pivot pins to the central portions of the arms respectively, and (6) mechanism operative automatically in response to swinging of the handle in a direction away from the second arm after application of the jaws to a pipe to move the second arm outwards away from the body and also to swing or tilt the second arm in such direction as to cause its jaw to move towards the jaw on the first arm.

As evidenced by Letters Patent No. 2,407,990, granted to me on September 24, 1946, it has heretofore been proposed in connection with a pipe wrench of the aforementioned type to connect the handle fixedly to the inner end of the body and to make the mechanism for automatically moving and tilting the second arm in the form of an angularly disposed toggle link which has one end thereof pivotally connected to the inner end of the second arm and its other end in pivotal relation with the outer end of the housing-like body and is so arranged or inclined that its one end extends away from the adjusting screw and its other end extends towards the adjusting screw. In practice it has been found that a pipe wrench having a toggle link of the aforementioned character as the mechanism for automatically moving and tilting the second arm is subject to the objection that the link does not operate positively and hence the jaw on the second arm after being applied to a pipe often slips in connection with swinging of the handle in a direction away from the second arm.

One object of the invention is to provide a pipe wrench which is an improvement upon, and eliminates the objection to, previously designed wrenches of the same general type or design and

2

is characterized by the fact that the handle is connected to the inner end of the housing-like body for limited pivotal movement in the plane of the body and jaw carrying arms and the mechanism for automatically moving the second arm outwards away from the handle and also swinging or tilting such arm so as to cause the jaw thereof to move towards the jaw on the first arm is operatively connected to the adjacent end of the handle in such manner that it is rendered effective when the handle is swung relatively to the body in a direction away from the second arm. By having the mechanism operatively connected to the handle outward and tilting movement of the second arm is positively obtained when the handle is initially swung in connection with a pipe turning operation and as a result the jaw on the second arm is precluded from slipping on the pipe.

Another object of the invention is to provide a pipe wrench of the last mentioned character in which the mechanism for automatically controlling combined outward and tilting movement of the second arm when the handle is swung relatively to the body in a direction away from the second arm consists of an inverted T-shaped lever which is disposed in the housing-like body and has one of its legs pivotally connected to the body at a point adjacent the inner end of the first jaw carrying arm, another of its legs pivotally connected to the inner end of the second arm, and its third leg fitting within a notch in the adjacent end of the handle.

A still further object of the invention is to provide a pipe wrench which is generally of new and improved construction, may be manufactured or fabricated at a comparatively low cost, effectively and efficiently fulfills its intended purpose, and is so constructed that it may be quickly and readily applied to, and removed from, a pipe or like article to be turned.

Other objects of the invention and the various advantages and characteristics of the present wrench will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like letters and numerals of reference denote corresponding parts throughout the several views:

Figure 1 is a side elevation showing a pipe

wrench embodying the invention with the handle swung toward the second arm and in the position it normally assumes preparatory to application of the jaws of the wrench to a pipe to be turned;

Figure 2 is a view partly in section and partly in side elevation showing the wrench after the handle has been swung relatively to the body in a direction away from the second arm and as a result of such swinging has caused the inverted T-shaped lever to move the second arm outwards 10 away from the body and also to tilt the arm so as to cause the jaw thereon to move towards the jaw on the first arm;

Figure 3 is a bottom perspective of the second arm, i. e., the arm that is movable to and from the fixed arm in response to manipulation of the adjusting screw;

Figure 4 is a perspective of the jaw that is pivotally mounted on the outer end of the second arm;

Figure 5 is a perspective of the U-shaped clip which serves to anchor one end of the spring for retracting the jaw on the second arm and also to hold such jaw in pivotally connected relation with the outer end of the second arm; and

Figure 6 is a perspective of the inverted T-shaped lever constituting the automatic mechanism for controlling movement of the second arm in response to swinging of the handle relatively to the body in a direction away from the second arm.

The wrench which is shown in the drawings constitutes the preferred form or embodiment of the invention. It is primarily designed or adapted for use in turning a pipe *p* and as its principal parts comprises an elongated housing-like body 10, a handle 11, a pair of oppositely disposed arms 12 and 13, and a pair of pipe engaging jaws 14 and 15.

The body 10 is preferably in the form of a one-piece metallic casting and consists of a bottom wall 16, a pair of side walls 17 and a top wall 18. The two side walls are spaced a small distance apart and have the lower portions thereof joined to the side margins of the bottom wall and their upper portions joined to the side margins of the top wall. As shown in Figures 1 and 2 the body is horizontally elongated and is open at its ends.

The handle 11 is in the form of a one-piece forging or metallic casting and is adapted to have one end thereof gripped by the user in connection with use of the wrench for pipe turning purposes. The other end of the handle extends into the inner end portion of the interior of the body 10 and is pivotally connected to the adjacent portion of the body by way of a horizontal pivot pin 19. The latter permits the handle to swing up and down to a limited extent relatively to the body 10 of the wrench and has its ends fixedly mounted within aligned or registering circular holes 20 in the inner end portions of the side walls 17 of the body. The central portion of the pivot pin 19 extends loosely through a circular hole 21 in the adjacent or proximal end of the handle 11. The hole 21 is located a small distance inwards of the extremity of the proximal end of the handle and such extremity is provided with a notch 22. As shown in Figure 2 the notch is arcuate and extends lengthwise of the handle.

The arm 12 projects outwards from the outer lower corner of the wrench body 10 and has its inner end formed integrally with the outer end of the bottom wall 16 and the outer lower portions of the side walls 17 of the body. The cen-

tral portion of the arm 12 is shaped to form a substantially vertical socket 23. The latter extends completely through the arm 12 and has open ends. The outer end of the arm 12 is of reduced width or thickness, as shown in Figures 1 and 2.

The arm 13 overlies the arm 12 and is movable to and from the latter, as hereinafter described. The inner end of the arm 13 extends through the open outer end of the body and is disposed in the upper central portion of the interior of the body. The central portion of the arm 13 is shaped to form a substantially vertical socket 24 and this extends completely through the arm 13 and is substantially vertically aligned with the socket 23 in the central portion of the arm 12. As will be noted from Figures 1 and 2 of the drawings, the movable arm 13 projects outwards a comparatively small distance beyond the fixed arm 12. An upstanding adjusting screw 25 serves as a medium or instrumentality for moving the arm 13 to and from the arm 12. This screw has its lower end disposed in the socket 23 and its upper end disposed in the socket 24. The lower end of the screw 25 has a right hand screw thread 26 and extends through a threaded hole in the central portion of a transversely extending pivot pin 27. The ends of this pivot pin are journalled or rotatably mounted in a pair of coaxial or aligned circular holes 28 in the sides of the socket defining central portion of the fixed arm 12. The pivot pin 27 permits the adjusting screw 25 to swing back and forth between the outer end of the arm 12 and the outer end of the body 10. The upper end of the adjusting screw is provided with a left hand screw thread 29 and extends through a threaded hole in the central portion of a transversely extending pivot pin 30. The ends of the pivot pin 30 are journalled or rotatably mounted in a pair of coaxial holes 31 in the sides of the socket defining central portion of the arm 13. The central portion of the adjusting screw 25 is provided with an enlarged cylindrical knob 32 for screw turning purposes. When the screw is turned in one direction the arm 13 moves towards the fixed arm 12 and when the screw is reversely turned or rotated the arm 13 is moved away from the fixed arm. By turning the adjusting screw 25 the arms 12 and 13 may be adjusted to receive pipes of different diameters. The pivot pin 30 permits the movable arm 13 to rock or tilt relatively to the adjusting screw 25.

The jaw 14 is associated with, and carried by, the fixed arm 12. It is located at the outer end of such arm and has a convex upper face and a flat bottom face. The upper face of the jaw 14 is provided from the front end thereof to the rear end with transversely extending pipe-engaging teeth 33. The bottom portion of the jaw 14 is provided with a pair of laterally spaced, depending, integral lugs 34 and these straddle the outer end of the fixed arm 12. A pin 35 extends through, and is fixed within, a transverse hole 36 in the outer end of the fixed arm 12. The ends of the pin project beyond the sides of the outer end of the arm 12 and fit within holes 37 in the depending lugs 34 on the jaw 14 in order to permit such jaw 14 to rock or tilt outwards and inwards with respect to the fixed arm 12. The outer portion of the upper surface of the fixed arm 12 is downwardly inclined with respect to the contiguous portion of the upper surface of the fixed arm 13 in order to permit the desired rocking or

tilting of the jaw 34. As shown in my aforementioned patent, each of the holes 37 in the depending lugs 34 of the jaw 14 may have a greater diameter than the pin 35 in order to provide proper looseness and enable the jaw readily to seat itself when it is applied to the pipe *p*.

The jaw 15 is associated with, and carried by, the movable arm 13. It underlies the outer end of the last mentioned arm and is disposed slightly outwards or forwards of the jaw 14. As shown in Figure 4, the jaw 15 is substantially semi-cylindrical and has a concave bottom face with downwardly extending transverse teeth 38. The curved or arcuate peripheral portion of the jaw 15 fits within a semi-circular recess 39 in the lower portion of the outer end of the movable arm 13. This recess extends lengthwise or longitudinally of the movable arm and has its rear or inner end portion in communication with a pocket 40. The latter is of less width than the recess 39 and is located between the recess and the socket 24 in the central portion of the movable arm 13. The recess 39 has the same radius as the jaw 15 and permits the jaw to turn or rotate back and forth about the axis or center thereof. The upper central portion of the jaw 15 has a longitudinally extending semi-cylindrical cutout 41 as shown in Figure 4. A U-shaped clip 42 and a pin 43 serve to hold the jaw 15 in connected relation with the outer end of the movable arm 13 while at the same time permitting the jaw to rock or rotate about its axis. The clip 42 is preferably in the form of a stamping of heavy gauge metal and consists of a crosspiece 44 and a pair of side pieces 45. It is so positioned or arranged that the crosspiece 44 and the adjacent ends of the side pieces 45 are disposed in the pocket 40 and the outer or free ends of the side pieces project into the cutout 41 in the upper central portion of the jaw 15. A transversely extending pin 46 holds the clip immovably in place. This pin has its ends fixedly mounted in aligned holes 47 in the portions of the movable arm 13 that define the pocket 40. The central portions of the pin extend through aligned holes in the ends of the clip side pieces 45 that are connected to the crosspiece 44. The outer or free ends of the side pieces of the clip 42 have the upper corners thereof cut away in such manner as to form fingers 48, the upper surfaces of which are convexly curved. The pin 43 extends transversely across the upper central portion of the jaw 15 and has its ends fixedly mounted in aligned holes in the jaw. The central portion of the pin 43 extends across the cutout 41 and rests on, and engages slidably, the convexly curved upper surfaces of the fingers 48. The pin 43 coacts with the fingers 48 on the free ends of the side pieces 45 of the clip 42 to hold the jaw 15 in connected relation with the outer end of the arm 13 while at the same time permitting the arm to rock or rotate about its center. The outer upper corners of the clip side pieces 45 define shoulders 49 which coacts with the pin 43 to limit counterclockwise turning or rotation of the jaw 15 as viewed in Figures 1 and 2. The jaw 15 is urged in a counterclockwise direction by way of a helical tension spring 50. The latter is located between the side pieces 45 of the clip 42 and has one end thereof anchored to the central portion of the pin 43. The other end of the spring is anchored to a transversely extending pin 51 which is lo-

cated outwards of the clip retaining pin 46 and has its ends mounted in aligned holes in the inner ends of the clip side pieces 45.

When the wrench is not in use the spring 50 rotates the jaw 15 in a counterclockwise direction until the pin 43 strikes against the shoulders 49. When the pin is in abutment with the shoulders the tooth equipped bottom surface of the jaw faces forwards and downwards and hence may readily be manipulated into gripping relation with the pipe *p*. In connection with application of the wrench to the pipe the jaw 15 is caused to rotate in a clockwise direction as viewed in Figures 1 and 2 until the teeth 38 are in firm gripping relation with the pipe.

In addition to the parts heretofore mentioned the wrench comprises an inverted T-shaped lever 52 which, after application of the jaws 14 and 15 of the pipe *p* and in connection with downward 20 swinging of the handle 11 relatively to the body 10, automatically causes the movable arm 13 to move outwards a small distance from the body and also to tilt in such direction as to cause the jaw 15 thereon to move towards the jaw 14. This lever 52 is located in the central portion of the interior of the body 10 and is preferably in the form of a one-piece heavy metal stamping. It consists of an outwardly extending leg 53, an inwardly extending leg 54 and an upwardly extending leg 55. The outwardly extending leg 53 is located a small distance above the outer end of the bottom wall 16 of the body 10 and is pivotally supported by way of a transversely extending pivot pin 56. The latter extends loosely 30 through a circular hole 57 in the outwardly extending leg 53 of the lever 52 and has its ends fixedly mounted in coaxial circular holes 58 in the side walls 17 of the wrench body 10. It forms the articulation point for the lever and permits the latter to swing upwards and downwards. The inwardly extending leg 54 has a rounded or curved outer extremity and this fits within the notch 22 in the extremity of the pivoted end of the handle 11. When the handle is swung downwards, i. e., in a counterclockwise direction as viewed in Figures 1 and 2, the lever 52 is caused to swing upwards relatively to the body. Reverse or upward swinging of the lever 11 results in the lever 52 swinging downwards. The upwardly extending leg 55 of the lever has a rounded upper end and this fits pivotally within a three-quarter round socket 59 in the inner end of the movable arm 13 of the wrench. In response to downward swinging of the handle 11 relatively to the body 10 the arm 13 is caused to move outwards and also tilt in a clockwise direction as viewed in Figures 1 and 2. When the lever 52 is swung downwards in response to upward swinging of the handle 11 with respect to the body 10 the movable arm 13 is caused to move inwards and also to tilt in a counterclockwise direction.

When it is desired to use the wrench to turn the pipe *p* the user first adjusts the movable arm 13 so as to space apart the jaws 14 and 15 to the proper extent to receive the pipe. The adjustment is effected by turning the screw 25 in one direction or the other, depending upon whether it is desired to move the arm 13 to or from the fixed arm 12. After the arm 13 is properly adjusted so that the jaws are set or positioned to receive the pipe the handle 11 is swung into the position shown in Figure 1 and the wrench is shifted bodily toward the pipe in order to bring the jaws into gripping relation with opposite

portions of the pipe. Following shift of the wrench towards the pipe the handle 11 is swung downwards. In connection with initial downward swinging of the handle the handle swings relatively to the body 10 and operates through the medium of the inverted T-shaped lever 52 to cause the movable arm 13 to move outwards from the body 10 and also to tilt in such direction as to cause the jaw 15 firmly to grip the adjacent portion of the pipe. After the jaw 15 is in firm gripping relation with the pipe further downward swinging of the handle will result in corresponding turning of the pipe ρ . To remove the wrench it is only necessary to swing the arm 11 upwards relatively to the body. Such swinging movement of the arm results in the lever 52 tilting the movable arm 13 so as to withdraw the jaw 15 from the pipe and also to move such arm bodily towards the body. If it is desired to turn the pipe ρ in a clockwise direction as viewed in the drawings instead of a counterclockwise direction the wrench is reversed, i. e., it is turned upside down.

The herein described wrench effectively and efficiently fulfills its intended purpose by reason of the fact that it includes the inverted T-shaped lever 52 which in response to swinging movement of the handle 11 relatively to the body 10 in a direction away from the arm, causes the arm to move outwards and also to tilt to such an extent that its jaw 15 firmly grips the pipe. Due to its specific construction and design the wrench may be produced at a comparatively low cost. The adjusting screw 25 permits the movable arm 13 to be quickly adjusted to and from the fixed arm 12 in connection with application of the wrench to pipes of different diameters.

Whereas the wrench has been described as a medium for turning a pipe it is to be understood that it may be used to turn any other article. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. A pipe wrench comprising a body, a handle having one end thereof pivotally connected to the body, a first arm having one end thereof connected fixedly to said body and embodying at its outer end a laterally extending pipe-engaging jaw, a second arm disposed in opposed relation with the first arm and having its outer end provided with a laterally extending pipe-engaging jaw, an adjusting screw for moving the second arm to and from the first arm and having the ends thereof pivotally connected respectively to central portions of said arms, and means operative automatically in response to swinging of the handle in one direction relatively to the body after application of the jaws to the pipe to move the second arm outwards away from the body and also to swing or tilt said second arm in such direction as to cause the jaw thereon to move towards the jaw on the first arm, said means embodying a separately formed pivotally mounted lever extending between and operatively connected to said one end of the handle and the inner end of said second arm.

2. A pipe wrench comprising an elongated hollow body, a handle having one end thereof extending into, and pivotally connected to, one end of the body, a first arm having one end thereof

connected fixedly to the other end of body and embodying at its outer end a laterally extending pipe-engaging jaw, a second arm disposed in opposed relation with the first arm and having the outer end thereof provided with a laterally extending pipe-engaging jaw and its inner end extending into said other end of the body, an adjusting screw for moving the second arm to and from the first arm and having the ends thereof pivotally connected respectively to central portions of said arms, and means operative automatically in response to swinging of the handle in one direction relatively to the body after application of the jaws to the pipe to move the second arm outwards away from the body and also to swing or tilt said second arm in such direction as to cause the jaw thereon to move towards the jaw on the first arm, said means embodying a separately formed pivotally mounted lever disposed within the body and extending between and operatively connected to said one end of the handle and the inner end of said second arm.

3. A pipe wrench comprising an elongated body, a handle having one end thereof pivotally connected to one end of the body at a point inwards of its extremity so that it is capable of swinging back and forth to a limited extent relatively to the body, a first arm having one end thereof connected fixedly to the other end of the body and embodying at its outer end a laterally extending pipe-engaging jaw, a second arm disposed in opposed relation with the first arm and having its outer end provided with a laterally extending pipe engaging jaw, an adjusting screw for moving the second arm to and from the first arm and having the ends thereof pivotally connected respectively to central portions of said arms, and means operative automatically in response to swinging of the handle relatively to the body in a direction away from the second arm and after application of the jaws to the pipe to move the second arm outwards away from the body and also to swing or tilt said second arm in such direction as to cause the jaw thereon to move towards the jaw on the first arm, said means embodying a T-shaped lever consisting of a first leg pivotally connected to the body at a point adjacent the inner end of the first arm, a second leg operatively connected to the extremity of said one end of the handle, and a third leg in pivotally connected relation with the inner end of said second arm.

4. A pipe wrench comprising an elongated hollow body, a handle having one end thereof extending into one end of the body and pivotally connected thereto at a point inwards of its extremity so that it is capable of swinging back and forth to a limited extent relatively to said body, a first arm having one end thereof connected fixedly to the other end of the body and embodying at its outer end a laterally extending pipe-engaging jaw, a second arm disposed in opposed relation with the first arm and having the outer end thereof provided with a laterally extending pipe-engaging jaw and its inner end projecting into said other end of the body, an adjusting screw for moving the second arm to and from the first arm and having the ends thereof pivotally connected respectively to central portions of said arms, and means operative automatically in response to swinging of the handle relatively to the body in a direction away from the second arm and after application of the jaws to the pipe to move the second arm outwards

away from the body and also to swing or tilt said second arm in such direction as to cause the jaw thereon to move towards the jaw on the first arm, said means embodying a T-shaped lever disposed within the body and consisting of a first leg connected pivotally to the body at a point adjacent the inner end of the first arm, a second leg operatively connected to the extremity of said one end of the handle, and a third leg in pivotally connected relation with the inner end of said second arm.

5. A pipe wrench comprising an elongated hollow body, a handle having one end thereof extending into one end of the body, pivotally connected thereto inwards of its extremity so that it is capable of swinging back and forth to a limited extent relatively to said body, and provided in said extremity with a notch, a first arm having one end thereof fixedly connected to the other end of the body and embodying at its outer end a laterally extending pipe-engaging jaw, a second arm disposed in opposed relation with the first arm and having the outer end thereof provided with a laterally extending pipe-engaging jaw and its inner end projecting into said other end of the body, an adjusting screw for moving the second arm to and from the first arm and

5 having the ends thereof pivotally connected respectively to central portions of said arms, and means operative automatically in response to swinging of the handle relatively to the body in a direction away from the second arm and after application of the jaws to the pipe to move the second arm outwards away from the body and also to swing or tilt said second arm in such direction as to cause the jaw thereon to move towards the jaw on the first arm, said means embodying a T-shaped lever disposed within the body and consisting of a first leg connected pivotally to the body at a point adjacent the inner end of the first arm, a second leg extending into 15 the aforesaid notch, and a third leg connected pivotally to the inner end of said second arm.
